UNITED STATES PATENT OFFICE.

GEORGE HANCOCK, OF HOLYOKE, MASSACHUSETTS.

IMPROVEMENT IN LOOMS.

Specification forming part of Letters Patent No. 43,848, dated August 16, 1864.

To all whom it may concern :

Be it known that I, GEORGE HANCOCK, of Holyoke, in the county of Hampden and Commonwealth of Massachusetts, have invented a new and useful Improvement in Looms for Weaving Woolen Cloth, which I denominate an "Eccentric Shed-Motion," said improvement relating to the manner of raising and lowering the harnesses, or of opening and closing the shed in certain varieties of "fancy looms," so called, for weaving woolen goods; and I do hereby declare that the following is a full, clear, and exact description of the construction and operation of the same, reference being had to the annexed drawings, making part of this specification.

Similar letters refer to like parts in all the drawings, in which—

Figure 1 is an end elevation of a woolen-loom, with the eccentric shed-motion attached to the main shaft thereof. Fig. 2 is a front view of the eccentrics. Fig. 3 is a side view of said eccentrics with a portion of the main shaft of the loom, which imparts motion to them; and Figs. 4, 5, 6, 7, 8, and 9, represent the several parts of the said eccentrics in detail.

The nature of my invention consists in attaching to the main or crank shaft of certain forms of woolen-loom, two variable eccentrics, which actuate, respectively, the elevating and depressing rods, and thus raise and lower such harnesses as the chain-motion brings into action.

This invention does not control or in any way affect the pattern and style of the cloth to be woven, but is intended to open and close the shed, or raise and lower the harnesses in a woolen-loom by a uniform and easy motion, and with the least injury to the warp. A crank-motion which actuates one rod while the other is moved by a lever attached to the first is in common use for this purpose, as also are the "rocker-plates" and various other devices, said devices being liable to many objections, which this invention, after due trial, is believed to obviate.

The following is a description of the construction and operation of my invention:

Fig. 1 is an end view of a woolen-loom, in which the variable eccentrics A and B are attached to the main shaft S, Fig. 3. These eccentrics carry the rigid studs a and b, which are

attached by set-screws g g to the elevator and depressor rods C and D. (D not fully shown in Fig. 1, see Fig. 3.)

The elevator-rod D carries the leveler E and the knife M, and the depressor C carries the leveler F and the knife N. A crank-pin in the face of the eccentric B communicates motion by a crank-rod, L, to the shaft K of the chain motion, which motion regulates the pattern or style of cloth to be woven. The elevator and depressor rods work in guides, as at G.

H is the lay or lathe, and I the connecting-rod. The action of the levelers E and F and of the knives M and N is well known in controlling the movement of the harnesses, and need not be described. Only those parts of the loom appertaining to this invention have been shown in the drawings.

The eccentrics may be constructed as follows: The outer one, B, consists of three parts, a circular slotted plate, B', Figs. 5 and 6, having a grooved edge, which is encircled by the ring, Fig. 4. This ring is made in two sections, c and d, connected by screws.

A hub-plate, P, Fig. 8, keyed upon the crank-shaft S, gives motion to the eccentric B, and also to the eccentric A, which is constructed like B, except that the circular plate A', Fig. 7, has, in addition to the slots s s, an aperture, through which the crank-shaft S passes to the hub-plate P, this aperture being elongated to admit of different positions of the plate A' with reference to the shaft S. The circular plates A' and B' are attached by set-screws to the hub-plate P, and by means of the slots s s may be set in any position, and thereby afford a greater or less thrust and open the shed to a greater or less extent.

I am aware that variable eccentrics may be constructed in various ways, and do not confine myself to the construction herein set forth.

I am aware, as already stated, that a single crank-motion has been used for moving the lifter, and through that the depressor rods, and that the thrust thereof could be varied; but the mechanical difficulties in the construction and use of two cranks of variable thrust, attached, respectively, to the lifter and depressor rods, are completely overcome by this invention.

Some of the advantages resulting from the

use of this invention upon that class of woolen-
looms to which it is applicable, I conceive
to be, first, such an action of the loom is
obtained as is easier for the warp and less lia-
ble to break the yarn, as has been demon-
strated by careful trial; second, by this in-
vention the lifter and depressor rods are ren-
dered independent of each other, thereby af-
fording greater facility in weaving; third, a
more regular motion is obtained, and there-
fore less power is required to actuate the
loom; fourth, a loom with this motion at-
tached thereto is more simple, more easily
repaired, and affords more ready access to the
parts thereof by the operator; fifth, it has
been ascertained by actual trial, continued
for several months, that a loom having this
attachment can be run at a higher speed, and

that from this cause, and the fewer stoppages
on account of broken threads in the warp, a
very considerable increase is obtained in the
number of yards woven.

I do not claim, broadly, moving the har-
nesses of looms by motion derived from ec-
centrics, as various applications of that prin-
ciple are in use; but

What I claim as my invention, and desire
to secure by Letters Patent, is—

The combination of variable eccentrics with
the lifter and depressor rods, respectively,
and actuating the harnesses thereby, substan-
tially as and for the purposes set forth.

GEORGE HANCOCK.
